(57) **CLAIM**

The ornamental design for a food plate, as shown and described.

DESCRIPTION

FIG. 1 is a front, right, and top perspective view of a food plate showing our new design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of portion 9 shown in FIG. 1;

FIG. 10 is a perspective view of the food plate thereof but showing an alternate position; and,

FIG. 11 is a perspective view of the food plate thereof but showing another alternate position.

The dash-dash broken lines in the drawings depict portions of the food plate that form no part of the claimed design. The remaining dash-dash broken lines depicting some knives placed in the front plate shown in FIG. 11 represent environmental subject matters and form no part of the claimed design. The dot-dash broken lines represent boundaries of the enlarged portion and form no part of the claimed design.

1 Claim, 11 Drawing Sheets
